UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EDGE-BURNISHING MACHINE.

1,280,710.

Specification of Letters Patent.

Patented Oct. 8, 1918.

Application filed January 13, 1916. Serial No. 71,902.

To all whom it may concern:

Be it known that I, PERLEY R. GLASS, a citizen of the United States, residing at Brookline, in the county of Norfolk and 5 State of Massachusetts, have invented certain Improvements in Edge-Burnishing Machines, of which the following description, in connection with the accompanying drawings, is a specification, like reference 10 characters on the drawings indicating like parts in the several figures.

This invention relates to leather working machines and is herein illustrated in connection with a machine for burnishing the 15 edges of pieces of upper leather.

It is customary with some grades of leather to finish the edges by burnishing them and thereby to avoid the more expensive process of skiving and folding said 20 edges.

A feature of the present invention comprises a tool for operating upon the stock, and means for feeding the stock forward and back intermittently in operative relation to said tool, the extent of the forward movements being greater than that of the backward movements. In the illustrative 25 machine a burnishing tool is caused to oscillate in contact with the edge of a piece of leather fed in the manner described above, the oscillations of the tool with respect to the feed being so timed that the rubbing action of the tool at any given instant takes place in a direction counter to the direction 30 of feed at that instant.

This and other features of the invention including certain details of construction and combinations of parts will be described in connection with an illustrative machine and 40 pointed out in the appended claims.

Referring now to the accompanying drawings,—

Figure 1 is an elevation of a machine in which the present invention is embodied;

45 Fig. 2 is a section on the line 2—2 of Fig. 1, certain parts of the frame having been omitted, and

Fig. 3 is a detail perspective showing a piece of stock in the process of having its 50 edge burnished.

Before going into the details of construction the general mode of operation of the machine as best illustrated in Fig. 3, will be described. The burnishing tool 1, which

is oscillated in the manner indicated by the 55 arrows, is provided with a groove 101 to receive the edge of the stock 100, said stock being held down upon a feed roll 3 by a spring-pressed disk 5; and to the feed roll is imparted an unequal oscillation, that in 60 the forward direction being of greater extent than that in the rearward direction as indicated by the arrows. The timing of the respective oscillations of the burnishing tool and feed roll is such that the operative 65 portion of said tool is always moving in a direction counter to that of the stock, the action of the tool upon the stock during the rearward movement of said stock being consequently exerted upon a less extent of the 70 edge of said stock than is its action upon the forwardly moving stock. The result of this procedure is to approximate the effect produced by manual burnishing in that the edge of the stock is rubbed first in one direc- 75 tion and then in the other.

The disk 5 is mounted in a casing 7 having a slotted ear 9 through which passes the stem of a set screw 11 for holding said casing, and with it said disk, in adjusted horizontal and angular position. A coiled spring 13, the tension of which may be varied by turning the thumb screw 15, holds the disk down upon the stock, suitable ball bearings being provided to take respectively the end 80 85 thrust and the lateral thrust of the stem of said disk.

The burnishing tool 1 is fastened by a clamp 17 to a holder 19 which is splined to an upright shaft 21. A groove formed in 90 the holder 19 receives the arms and base of a yoke 23 between the arms of which is fastened a block 25 having rotatably mounted therein a screw threaded stem 27. A collar 29 threaded on said stem and held between 95 two ears on the frame of the machine furnishes means for raising and lowering said stem and with it the burnishing tool 1. A coiled spring 31 located between a collar on the shaft 21 and the top of the tool holder 100 19 prevents chattering of the parts. The shaft 21 has formed upon it a screw 33 of steep pitch with which a nut 35 co-operates, said nut having a slotted extension to receive a crank-pin 37 on a disk which is fast 105 to the driving shaft 39. Two suitable ball-bearings 41, 43 receive the upward and downward thrust of the shaft 21. With the

construction described above rotation of the shaft 39 produces oscillation of the shaft 21 and consequently of the burnishing tool 1.

The feed roll 3 is mounted upon a horizontal shaft 45 which carries fast to its inner end a gear 47 said gear being driven first in one direction and then in the other by a peculiarly operated worm 49. The worm is both rotated and reciprocated. Rotation of the worm causes counter-clockwise rotation of the gear 47 as viewed in Fig. 2; downward movement of the worm accelerates the rotation of said gear, and upward movement of the worm counteracts the effect of its rotation and causes rotation of the gear 47 in a clockwise direction. The extent of the clockwise rotation which results from this compound movement of the worm is less than the extent of the counter-clockwise movement so that the stock is advanced step-by-step past the burnishing tool.

The screw 49 is formed upon a rod 51, the lower end of said rod passing through a collar 53 pivoted at 55 to a rod 57 which may be adjusted to bring the worm 49 into proper mesh with the gear 47 and then locked in adjusted position by manipulating the nuts 57. The upper end of the rod 51 is slidably connected with but held from rotation with respect to an upright spindle 59 said spindle having bearings in a carrier 61 which is loosely hung on the driving shaft 39 and having fast to it near its upper end a gear 63 which meshes with a gear 65 on the driving shaft 39. When, therefore, the shaft 39 is rotated the worm 49 is rotated but is free to reciprocate vertically.

Reciprocation of the stem 51 is accomplished by the following mechanism. Fast to the stem 51 are two collars 67; and between said collars and separated from them by ball bearings is a loose collar 69 to which is pivoted at 71 one end of a link 73 to the other end of which is pivoted a connecting-rod 75 having at its upper end an eccentric strap 77 which encircles an eccentric on the shaft 39. A fulcrum block 79 adjustably held in a slot in the link 73 by a screw 81 is pivoted to the lower end of a link 83 the upper end of which is pivoted at 85 to the frame of the machine. In order to adjust the link 83 angularly and to hold it in adjusted position a link 87 is pivoted at one end at 89 to the link 83 and at the other end 55 at 91 to a screw threaded rod 93 which may be moved longitudinally by turning a thumb-nut 95 and may be locked by means of a wing nut 97.

The operation of the feed mechanism which has been described above is as follows:—Rotation of the shaft 39 through the gears 63 and 65 and the spindle 59 causes rotation of the worm 49 and consequently of the feed roll shaft 45 in a counter-clockwise direction as viewed in Fig. 2. In ad-

dition to this rotation of the worm 49 there is imparted to it, through the rod 75 and link 73, a complete vertical reciprocation at each revolution of the shaft 39. The worm 49 thus has two functions one to operate as a worm proper and the other to operate as a rack on the gear or pinion 47. Downward movement of the worm accelerates the counter-clockwise rotation of the gear 47 and upward movement of the worm reverses the direction of rotation of said gear. Consequently the stock is fed forward and back by a series of intermittent movements of which the forward movements are of greater extent than that of the rearward movements so that the final result is to advance the stock. An adjustable edge gage 99 is provided to facilitate guiding the stock properly to the tool.

Although the invention has been set forth in connection with a particular machine, it should be understood that the invention is not limited in the scope of its application to the particular machine shown and described.

Having thus described my invention, I claim as new and desire to secure by Letters Patent:

1. A machine of the class described, having, in combination, a tool for operating upon a piece of stock, and means for feeding the stock forward and back intermittently in operative relation to said tool, the extent of the forward movements being greater than that of the backward movements.

2. A machine of the class described, having, in combination, a burnishing tool, and means for feeding the stock forward and back intermittently with its edge in engagement with said tool, the extent of the forward movements being greater than that of the backward movements.

3. A machine of the class described, having, in combination, a burnishing tool, means for oscillating said tool, and means for feeding the stock forward and back intermittently with its edge in engagement with said tool the extent of the forward movements being greater than that of the backward movements.

4. A machine of the class described, having, in combination, means for feeding a piece of stock forward and back intermittently, the extent of the forward movements being greater than that of the backward movements, and means for rubbing the edge of the stock in a direction counter to the direction of movement of said stock at any given instant of the rubbing operation.

5. A machine of the class described, having, in combination, a burnishing tool, a roll for feeding stock past said tool, and means for oscillating said feed roll forward and back, the extent of the forward oscilla-

1,280,710
stock, and means for oscillating said tool.

11. In a burnishing machine, a burnishing tool, a feed mechanism, and means for synchronously moving the feed mechanism and the burnishing tool forward and backward, the feeding movement being at all 40 times opposite in direction to the burnishing movement.

In testimony whereof I have signed my name to this specification.

PERLEY R. GLASS.

Obtained for five cents each, by addressing the "Commissioner of Patents, Washington, D. C."

ing, in combination, a tool upon a piece of stock, a feed mechanism for the stock, a worm and gear, 15 said roll, and means for reciprocating said worm.

8. A machine of the class, in combination, a tool upon a piece of stock, a feed mechanism for the stock, a worm and gear, 20 said roll, means for rotating said worm, and means for extent of said reciprocation.

Copies of this patent may be obtained for five cents each, by addressing the "Commissioner of Patents, Washington, D. C."
